UNITED STATES PATENT OFFICE.

WEBBER S. RUSSELL, OF CHICAGO, ILLINOIS.

INTERNAL-COMBUSTION ENGINE.

1,043,254.

Specification of Letters Patent.

Patented Nov. 5, 1912.

Application filed March 18, 1911. Serial No. 615,235.

To all whom it may concern:

Be it known that I, WEBBER S. RUSSELL, a citizen of the United States, residing at Chicago, county of Cook, State of Illinois, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

In two-cycle internal combustion engines there is a power impulse during each revolution of the crank shaft, the combustion gases being discharged and a new supply of gaseous fuel delivered to the cylinder during a small fraction of the movement of the piston at the end of its power stroke and at the beginning of the compression stroke. One of the chief problems is that of clearing the cylinder of the waste gases and filling it with the fuel charge during the short space of time which may be allowed for this purpose. In the usual types of two-cycle engines the crank case is made tight so that it will serve as a reservoir. On the compression stroke, a supply of gaseous fuel is drawn into the crank case and it is slightly compressed when the piston returns on its power stroke. Just before the end of the power stroke is reached the piston uncovers an exhaust port which permits the products of combustion to pass out of the cylinder. Shortly thereafter a port leading from the interior of the crank case to the cylinder is uncovered by the piston and the slightly compressed fuel flows from the crank case into the cylinder. At the beginning of the return stroke of the piston it first covers the inlet port to the cylinder and then the exhaust port, the charge of combustible being thereafter confined in the cylinder and being compressed during the remainder of the return stroke.

At the time the exhaust port is uncovered, the pressure within the cylinder is still considerably above atmospheric pressure and consequently the products of combustion begin to flow rapidly out of the exhaust port. If the exhaust pipe leading from the exhaust port is of any considerable length, the inertia of the mass of spent gases flowing through the same is sufficient to produce a partial vacuum in the cylinder. Therefore, when the inlet port is opened, the incoming

charge is both pushed in by the pressure in the crank case and pulled in by the vacuum in the cylinder. The result is that part of the charge is invariably sucked out of the exhaust port and wasted. Furthermore, since it is impossible to produce a complete vacuum in the cylinder, some of the products of combustion remain and dilute the charge of combustible and thus produce a weaker power stroke following the next explosion than would be the case if all of the products of combustion had been discharged.

In order properly to scavenge the cylinder of burnt gases it is necessary to admit air into the cylinder as the products of combustion leave it. The incoming charge may then be made slightly richer in its combustible component so that the resulting mixture, when it is diffused in the air present in the cylinder, contains air and combustible in the proper proportions. Various mechanical contrivances, in the form of attachments to an ordinary engine have been proposed and used to some extent for the purpose of scavenging the cylinders of burnt gases.

My invention has for its object the complete clearing of the engine cylinder in a simple and reliable manner of the products of combustion during each cycle of operations and the introduction of the combustible without waste or loss of the latter.

The various features of novelty whereby my invention are characterized will herein-after be pointed out with particularity in the claims; but, for a full understanding of my invention and of its objects and advantages, reference may be had to the following detailed description taken in connection with the accompanying drawings, wherein:

Figure 1 is a central longitudinal section of a two-cycle engine arranged in accordance with one form of my invention; and Fig. 2 is a view similar to Fig. 1 showing an elaboration of the principle of my invention.

Referring to Fig. 1 of the drawings, 1 represents the cylinder and 2 the inclosed crank case of a two-cycle internal combustion engine. 3 is the piston, 4 the crank shaft and 5 the connecting rod or piston rod extending from the piston to the crank shaft. The means for igniting the charge is illustrated as taking the form of a spark plug 6. 7 and 8 are respectively an exhaust port and an inlet port, the piston acting as

a valve controlling both, and the exhaust port being so located that it will be opened shortly before the end of the power stroke of the piston is reached and also before the 5 inlet port is opened. The inlet port is connected to the interior of the crank case by a conduit 9. The fuel is supplied to the engine through a carbureter 10 whose delivery end leads into the interior of the crank case.

10 All of the parts heretofore described may take any usual or preferred forms since they, of themselves, form no part of the present invention.

The piston, as is usual, is provided with 15 a suitable deflector, 11, adapted to direct the inflowing gases longitudinally of the cylinder and away from the exhaust port.

In the drawing the piston is shown as just approaching the end of the power 20 stroke, the exhaust port having been opened to permit the products of combustion to escape. In accordance with my invention I provide for admitting air into the cylinder at this point in the cycle of operation in a 25 simple manner so that instead of a partial vacuum being produced, fresh air is drawn into the cylinder to take the place of the products of combustion. I introduce the air through a port 12 which, like the ports 7 30 and 8, is controlled by the piston; this auxiliary port being so situated longitudinally of the cylinder that it will be opened only after the exhaust port has been at least partially opened and before the fuel-inlet 35 port has been uncovered. By this arrangement, the major portion of the products of combustion rush out through the exhaust port and lower the pressure within the cylinder to a point below atmospheric pressure, 40 and then the air port is opened and fresh air rushes in. I prefer to place the air port so that it will have the same relation to the deflector on the piston as has the fuel inlet port. Consequently the incoming air will 45 flow along the side of the cylinder, then over to the opposite side and down toward the exhaust port, sweeping the combustion gases before it and clearing the cylinder more or less completely. Then, when the gaseous 50 fuel enters, it follows the same path as the air which preceded it, pushes the air before it and completes the clearing of the cylinder.

It will be seen that before the combustible can flow out of the exhaust port, not only all 55 of the products of combustion, but also a considerable bank of fresh air must first be discharged, and consequently there is little opportunity for any of the combustible charge to escape before the exhaust port is closed on the return of the piston.

It will therefore be seen that I have provided means for effectively scavenging the cylinder of a two-cycle engine without loss of combustible by the mere addition of an 65 extra port; there being substantially no ad-

dition to the initial cost of the engine and no addition to the up-keep cost.

The degree of vacuum which the outgoing products of combustion tend to produce in the cylinder determines the amount 70 of fresh air which is drawn in and it depends upon the mass of the gas column between the exhaust port and the final outlet to the air. By connecting an exhaust pipe, such as 13, with the exhaust port, a column 75 of flowing gas the length of the pipe is produced whenever the exhaust port is uncovered. The exhaust pipe may be lengthened or shortened to vary the amount of air which will be drawn into the cylinder. The longer 80 the exhaust pipe the more effective will be the clearing of the cylinder; this being true as the pipe is enlarged until its cubic content is equal to several times that of the cylinder.

85 In Fig. 2 I have shown an arrangement in which the principles which I have just outlined are extended somewhat. In this figure the engine and its principal parts are the same as in Fig. 1, and, as the mode of operation is the same, I shall not describe it in detail but call attention to the fact that in the two figures I have marked corresponding parts with the same numerals, adding the exponent *a* in Fig. 2 wherever there is 90 some formal departure from the corresponding 95 element in Fig. 1.

It will be seen that the air-inlet port remains open during the entire time that the combustible charge is admitted and for a 100 short time thereafter. It may therefore happen that because all of the combustible must flow directly past the air port, some will escape through the air port and be lost. To prevent this I have provided the air port 105 12^a, in the arrangement shown in Fig. 2, with a means for preventing flow therethrough in the outward direction. This may conveniently take the form of a little flap valve 14 of leather or other light 110 flexible material. In the arrangement illustrated, the member 14 is contained in a housing 15 situated over the inlet end of the air port. It will be seen that the light flap valve has little mass and inertia so that 115 it will offer no appreciable resistance to the inflow of air but will close under pressure within the cylinder and prevent escape of the combustible. I am able to use a valve of leather or the like because it is not in contact 120 with the burning gases in the cylinder, the air port being closed by the piston at the time the explosion takes place, and the bulk of the products of combustion having escaped through the exhaust port before the 125 air port is opened.

It will be seen that the path followed by the inflowing fresh air and by the fuel is along the sides and across the end of the cylinder. This leaves the fluid in the cen- 130

ter of the cylinder and directly above the piston in a more or less dead condition and may result in permitting some of the products of combustion to remain in the cylinder. To obviate this I have placed in the end of the cylinder a second air-inlet port 16, controlled by a suitable inwardly-opening check valve 17; the port being so arranged that inflowing air will sweep diagonally across the cylinder toward the exhaust port 7^a. In this way all danger of pocketing some of the products of combustion is overcome because every part of the cylinder will be swept by a stream of fresh air flowing directly or indirectly toward the exhaust port.

The air-inlet port 16 may, if desired, be supplied with an approach in the form of a pipe, as indicated at 18; affording the advantage of a moving column of air whose inertia will prevent the check valve from closing as soon as it otherwise would, and co-operating with the moving column of exhaust gases to force fresh air into the cylinder.

If desired, a small revoluble wind wheel 19, having considerable mass, may be mounted in the exhaust pipe 13^a, the wheel being set in rotation when the combustion gases first begin to escape, and continuing to rotate and act as a suction fan when the pressure in the cylinder drops to or below atmospheric pressure. Thus assistance is given the moving column of gases in producing a partial vacuum in the cylinder.

It will thus be seen that I have provided a simple and effective means for insuring that the cylinder of a two-cycle engine will always have in it a charge free from spent gases at the time of firing, and for preventing waste of fuel by letting it escape through the exhaust port at the time a fresh charge is drawn into the cylinder.

While I have illustrated and described only a single form of my invention disclosing various extension of what I believe to be a new arrangement of parts, I do not intend to be limited to the structural details so illustrated and described; but desire to cover all forms and arrangements which fall within the terms employed in the definitions of my invention constituting the appended claims.

I claim:

1. In a two-cycle internal combustion engine, a cylinder having oppositely disposed fuel-inlet and exhaust ports, an engine piston movable in said cylinder and serving as a valve to control said ports, the parts being so arranged that the exhaust port and then the fuel-inlet port are opened as the piston approaches the end of its power stroke, said cylinder having an air-inlet port leading to atmosphere and controlled by the piston and arranged adjacent to and slightly in advance of the fuel-inlet port so

as to be opened by the piston after the exhaust port and before the fuel-inlet port, a deflector on said piston arranged to direct air and fuel flowing into the cylinder through said air-inlet port and fuel-inlet port lengthwise of the cylinder along the adjacent side, said cylinder having a second air-inlet port leading to atmosphere at the end thereof and situated so as to deliver air diagonally across the cylinder toward the exhaust port, and an inwardly-opening check valve associated with said second air-inlet port.

2. In a two-cycle internal combustion engine, a cylinder having oppositely disposed fuel-inlet and exhaust ports, an engine piston movable in said cylinder and serving as a valve to control said ports, the parts being so arranged that the exhaust port and then the fuel-inlet port are opened as the piston approaches the end of its power stroke, said cylinder having also an air-inlet port leading to atmosphere and arranged adjacent to and slightly in advance of the fuel-inlet port so as to be opened after the exhaust port and before the fuel-inlet port, and a light flap valve arranged to prevent flow of gases outwardly through said air-inlet port.

3. In a two-cycle internal combustion engine, a cylinder having oppositely disposed fuel-inlet and exhaust ports, an engine piston movable in said cylinder and serving as a valve to control said ports, the parts being so arranged that the exhaust port and then the fuel-inlet port are opened as the piston approaches the end of its power stroke, said cylinder having also an air-inlet port leading to atmosphere and arranged adjacent to and slightly in advance of the fuel-inlet port so as to be opened by the piston after the exhaust port and before the fuel-inlet port, and a flexible flap valve having a small inertia arranged outside of the cylinder for preventing a flow of gases outwardly through said inlet port.

4. In a two-cycle internal combustion engine, a cylinder having oppositely disposed fuel-inlet and exhaust ports, an engine piston movable in said cylinder and serving as a valve to control said ports, the parts being so arranged that the exhaust port and then the fuel-inlet port are opened as the piston approaches the end of its power stroke, said cylinder having also an air-inlet port leading to atmosphere and arranged adjacent to and slightly in advance of the fuel-inlet port so as to be opened by the piston after the exhaust port and before the fuel-inlet port, a chamber communicating with the outer end of said inlet port, said chamber having a port leading to atmosphere, and a flexible flap valve having little inertia associated with the last mentioned port for preventing an outward flow of gas therethrough.

5. In a two-cycle internal combustion en-

gine, a cylinder having oppositely disposed fuel-inlet and exhaust ports, an engine piston movable in said cylinder and serving as a valve to control said ports, the parts being so arranged that the exhaust port and then the fuel-inlet port are opened as the piston approaches the end of its power stroke, said cylinder also having an air-inlet port leading to the atmosphere at a point adjacent to and slightly in advance of the fuel-inlet port so as to be opened after the exhaust port and before the fuel-inlet port, said air inlet port being arranged diagonally

through the wall of the cylinder so as to direct air flowing therethrough away from the exhaust port, and a deflector on the piston arranged to deflect air entering the fuel-inlet port and cause it to flow along the adjacent side of the cylinder.

In testimony whereof, I sign this specification in the presence of two witnesses.

WEBBER S. RUSSELL.
